UNITED STATES PATENT OFFICE.

WILLIAM H. BURKE, OF HAVERHILL, MASSACHUSETTS, ASSIGNOR TO UNITED SHOE MACHINERY COMPANY, OF PATERSON, NEW JERSEY, A CORPORATION OF NEW JERSEY.

ROLL FOR OPERATING UPON BOOTS AND SHOES.

1,217,405.

Specification of Letters Patent. Patented Feb. 27, 1917.

Application filed June 10, 1915. Serial No. 33,380.

To all whom it may concern:

Be it known that I, WILLIAM H. BURKE, a citizen of the United States, residing at Haverhill, in the county of Essex and State 5 of Massachusetts, have invented certain new and useful Improvements in Rolls for Operating upon Boots and Shoes; and I do hereby declare the following to be a full, clear, and exact description of the invention, such 10 as will enable others skilled in the art to which it appertains to make and use the same.

The present invention relates to rolls for operating upon boots and shoes, and more 15 particularly to rolls employed for leveling the soles of boots and shoes.

It will be obvious to those skilled in the art that as a finished sole after it has been incorporated in a boot or shoe, varies both 20 in width and transverse curvature throughout the length of the sole, it is desirable to provide means for adjusting the leveling roll in order that the roll shall operate most efficiently upon each portion of the shoe sole.

25 The object of the present invention is to provide certain improvements in a roll for operating upon boot and shoe soles which enables both the size and shape of the roll to be varied. With this object in view a 30 feature of the invention contemplates the provision of a roll for operating upon boot and shoe soles comprising a continuous unbroken sole engaging surface extending lengthwise from end to end of the roll, and 35 means for varying the longitudinal contour of the roll. In the simplest and most efficient form of the invention which has yet been devised the roll consists of a series of sole engaging ribs extending continuously 40 from end to end of the roll, and means engaging with the ribs for varying the longitudinal contour of the roll.

Still further features of the invention consist in certain novel features of construction, 45 combinations and arrangements of parts hereinafter described and claimed, the advantages of which will be obvious to those skilled in the art from the following description.

50 In the accompanying drawings illustrating the preferred form of the invention; Figure 1 represents a front elevation partly in section of the improved roll; and Fig. 2 is a section upon the line 2—2 of Fig. 1, illus-

trating in dotted outline the position of a 55 shoe sole with relation to the roll.

According to the present invention the longitudinal contour of the leveling roll may be adjusted or varied as desired and the diameter of different portions of the roll is 60 also varied in order to permit the roll to operate most efficiently upon both the ball and shank portions of a shoe sole. In the illustrated embodiment of the invention a series of flexible ribs are secured to a rotary hub 65 between their ends and a pair of oppositely disposed spreader members project within the ends of the ribs to determine the separation of the ribs and the consequent contour of the roll. The spreader members are conveniently actuated by a common control 70 which causes the members to be moved simultaneously toward and from one another to insure an even spacing of the ribs at their opposite ends. The roll comprises a series 75 of ribs 2, each supported between their ends upon a rotary hub 4 and each rib extending continuously from end to end of the roll. Each rib is secured rigidly to the hub midway of its ends by a fastener member 5 and with this construction it will be obvious 80 that as the central portions of the ribs are secured to the hub, the diameter and shape of the central portion of the roll will be fixed. The hub 4 is secured to a shaft 7 85 journaled in the upper ends of stationary arms 8 and 9 and having a driving pulley 10 secured to one end by which the roll is conveniently actuated to beat out and level the sole of a shoe. The separation of the ends 90 of the ribs and the longitudinal contour of the roll is varied by a pair of oppositely disposed spreader members 12 which are splined upon the shaft 7 and are provided with peripherally grooved hubs 14 which 95 are operatively connected with actuating arms 15 serving to move the spreader members toward and from one another. It will be observed from an inspection of Fig. 1 that the spreader members are of a conical 100 form and project within the ends of the flexible ribs so that a movement of the spreader members toward and from one another serves to bend the ends of the ribs outwardly to a greater or less extent. In order 105 to move the spreader members simultaneously, each actuating arm 15 is fulcrumed upon the roll carrying head at 16 and is

provided with a second arm 17 extending therefrom, the two arms 17 being interconnected at their ends by gear teeth 18. The arms are conveniently actuated by a treadle rod 20 connected to one of the arms 17.

With this construction it will be obvious that the longitudinal contour of the leveling roll may be varied as desired and this is accomplished without interrupting the continuity of the sole engaging surfaces, or without forming any break in the leveling roll which would tend to mar or disfigure the surface of the sole.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A roll for operating upon boot and shoe soles, comprising a series of sole engaging ribs each extending continuously from end to end of the roll, and means engaging with the ribs for varying the longitudinal contour of the roll.

2. A roll for operating upon boot and shoe soles, comprising a series of ribs extending continuously from end to end of the roll, means for supporting the ribs in spaced relation to one another between their ends, and means for spreading the ends of the ribs apart to vary the longitudinal contour of the roll.

3. A roll for operating upon boot and shoe soles, comprising a shaft, a plurality of ribs supported upon the shaft in spaced relation to one another to present a substantially cylindrical surface to the shoe sole, and means for separating the ends of the ribs in a radial direction to vary the longitudinal contour of the roll.

4. A leveling roll comprising a series of ribs extending lengthwise of the roll, means for supporting the ribs midway of their ends in spaced relation to one another, and means engaging with the ribs to vary the diameter of the roll at the ends.

5. A roll for operating upon boot and shoe soles, comprising, a rotary hub, a series of flexible ribs secured to the hub midway of

their ends, and a spreader member projecting within the ends of the ribs to determine the separation of the ribs and the contour of the roll.

6. A roll for operating upon boot and shoe soles, comprising, a rotary hub, a series of ribs secured to the hub midway of their ends, a spreader member projecting within the ends of the ribs, and means for moving the member lengthwise of the roll.

7. A roll for operating upon boot and shoe soles, comprising, a series of ribs extending lengthwise of the roll, means for supporting the ribs midway of their ends, a pair of oppositely disposed spreader members projecting within the ribs at the opposite ends, and means for simultaneously moving the spreader members toward and from one another.

8. A roll for operating upon boot and shoe soles, comprising, a shaft, a hub secured to the shaft, a series of flexible ribs secured to the hub midway of their ends, a pair of conical members slidably mounted upon the shaft and projecting within the opposite ends of the ribs, arms engaging with the conical members, and means for simultaneously actuating the arms to move the conical members toward and from one another.

9. A roll for operating upon boot and shoe soles, provided with a series of beating out surfaces extending lengthwise of the roll and having a fixed diameter at its central portion, and means for varying the diameter of the outer ends of the roll.

10. A roll for operating upon boot and shoe soles, having in combination, a series of ribs extending lengthwise of the roll, means for supporting the ribs midway of their ends in fixed relation to one another, and means for varying the separation of the ends of the ribs.

11. A roll for leveling boot and shoe soles, comprising a continuous unbroken sole engaging surface extending lengthwise from end to end of the roll, and means for varying the longitudinal contour of the roll.

12. A roll for leveling boot and shoe soles, having in combination, a central portion, and tapered members movable toward and from the central portion to vary the longitudinal contour of the roll.

WILLIAM H. BURKE.
